Fig. 5

A cross-sectional diagram of a target assembly. It consists of four concentric rings. The innermost ring is divided into four quadrants by a crosshair. The center of the crosshair is shaded with diagonal lines. The number '25' is written in the lower quadrant of the inner ring. The number '24' is written in the upper quadrant of the inner ring. The number '51' is written in the upper quadrant of the middle ring. The number '32' is written in the lower quadrant of the outer ring. The number '33' is written in the lower quadrant of the inner ring. The number '10' is written in the lower quadrant of the outer ring. The number '19' is written in the upper quadrant of the outer ring. The number '1' is written in the lower quadrant of the outer ring.

MULTIPLE FUSE

Gerard McL. Cole, Chicago, Ill., assignor to
Nathan Goldman, Chicago, Ill.

Application July 5, 1932. Serial No. 620,886

6 Claims. (Cl. 200—125)

My invention relates to fuse plugs of the type wherein a plurality of fuse elements are so arranged that any fuse element may be placed in circuit without the necessity of replacing the 5 entire fuse.

It is the principal purpose of my invention to provide a device of this character in which the parts of the fuse which are burned are arranged in separate explosion chambers away from the 10 contact chamber wherein the movable contact engages the fuse element.

My invention also contemplates a novel construction for venting fuse chambers.

It is also a purpose of my invention to provide 15 in a device of this character a novel structure for making contact with the different fuse elements which structure also permits one to see when a fuse has been blown.

My invention also contemplates the provision 20 of a novel chamber structure which so places the weakened part of the fuse element as to cause quick extinction of the arc when the fuse is burned.

I will describe the preferred form of my invention by reference to the accompanying drawings wherein—

Fig. 1 is a view of the top of the fuse with certain parts thereof broken away to illustrate the top structure;

30 Fig. 2 is a section on the line 2—2 of Fig. 1;

Fig. 3 is a section on the line 3—3 of Fig. 2;

Fig. 4 is a section on the line 4—4 of Fig. 2;

Fig. 5 is a section on the line 5—5 of Fig. 2;

35 Fig. 6 is a perspective view showing the under-side of the cap;

Fig. 7 is a perspective view of a mounting ring used in securing the fuse elements in place;

Fig. 8 is a perspective view of the main casing with the bottom closure removed; and

40 Fig. 9 is a perspective view of the bottom.

Referring now in detail to the drawings, the main body part of the fuse consists of a casing 10 having therein, in the preferred form, four chambers such as 11, 12, 13, and 14 for four fuse elements. This casing is preferably molded and has a cavity at the top end to form a contact chamber at 15. Immediately below the contact chamber 15, the casing as shown has the annular shoulder or shelf 16, and the lips such as 17 in each 45 chamber 11 to 14 extend this shelf so as to provide only a narrow opening at 18 from the contact chamber 15 to the various fuse element chambers. At the other end of the casing 10, the bottom closure element 19 abuts against the 50 end of the casing and is non-rotatably interlocked

therewith by means of the projections 20 and sockets 21 on the casing and bottom closure respectively. The upper chamber 15 is closed by means of a cap 22 which is preferably of a transparent material, or at least has a portion thereof 60 transparent, for a purpose which will presently appear.

The casing 10, the bottom closure 19, and the cap 22 are held together by the center contact element 23 which element has a pin 24 extending 65 through suitable openings 25 and 26 in the bottom closure and casing respectively, and this pin 24 is, as shown most clearly in Fig. 2, bent over at 27 in the cap or otherwise secured against detachment. The end of the pin may be covered by 70 a suitable insulating cement such as 28.

The fuse elements 30 are located in various chambers and have their lower terminals passing through suitable guide grooves at the lower end of the casing 10 as indicated at 31 (see Figs. 75 2 and 8), and the fuse elements are then bent upwardly along the outside of the casing 10 where they contact with the shell contact 32. This shell contact has a lip at 33 fitting a shoulder on the tip element 19 and is screw-threaded on the exterior of the casing 10 by means of the broken threads such as are indicated at 34. At least one of the fuse elements is soldered to the screw shell 32 at 35 after the shell is mounted so as to prevent rotation of the shell. The other end of 80 85 the fuse element passes around the lip 17 and across the shelf 16 beneath a transparent mica sheet 36 which lies tightly against the tops of the fuse elements in the bottom of the chamber 15. The free ends of the fuse element are then 90 bent up and over the ring 37 seated in the chamber 15 which ring is constructed of insulating material.

This ring 37 is shown in perspective in Fig. 7 and, as shown, is notched at 38 to receive the 95 fuse elements. The material of the ring at one side of the notches 38 is inclined as indicated at 39 so as to enable a wiper contact 40 to slide off a fuse element seated in the notch 38 in one direction while the shoulders such as 41 opposite 100 the inclined portions 39 are sufficiently high to prevent rotation of the arm 40 in the opposite direction. This ring 37 and the outer rim of the chamber 15 have suitable projections and recesses such as 42 and 43 to prevent rotation 105 of the ring within the chamber 15. It will be noted that around the central opening 26, the casing 10 is provided with the upstanding boss 44 in the center of the chamber 15, and fitted around this boss is another ring 45 which coop- 110

erates with ring 37 to hold the mica sheet 36 tightly down against the shell 16 and also forms a bearing shoulder for the cover 22. The pin 24 has the arm 40 placed thereon in electrical contact therewith, and the cap 22 is grooved at 46 for reception of the contact arm 40 so as to rotate therewith. Contact arm 40 is also provided with an opening at 47 directly over the openings 18 through which the fuse elements 30 pass so that, 10 when the fuse blows at its weakened point, the discoloration of the mica is clearly visible through this opening and readily reveals the condition of the fuse element.

I have also provided a novel means for venting 15 the fuse chambers. Each chamber, as shown clearly in Fig. 8, has leading therefrom a vent groove 48 which groove leads to the central projection 49 at the bottom end of the casing. This projection extends into a recess 50 in the closure 20 19. The opening 25 is then made square or otherwise suitably grooved to allow escape of the gases downwardly from the recess 50, and the bottom end of the closure 19 has a plurality of 25 grooves as shown at 51 which allow the gases to escape laterally from the fuse.

When the fuse element is blown, it naturally discolors the mica sheet 36 directly over its weakened point, and the cover 22 is made transparent at least over the opening 47 so that one can see 30 the discoloration on the mica and thus know that the fuse at that point is blown. It is then only necessary to turn the cap a quarter revolution to bring a new fuse into place. The lips 17 at the point where the fuse elements are weakened make it necessary for the arc between the two burned ends of the fuse to pass around this lip, and this results in a quick quenching of the arc and consequently a less violent explosion.

From the above description, it is believed that 40 the construction and advantages of this device will be clear to those skilled in this art.

Having thus described one specific form of my invention, what I claim as new and desire to secure by Letters Patent is:

45 1. A multiple fuse plug provided with a casing having a plurality of explosion chambers arranged around a central axis and having a contact chamber at one end of said explosion chambers, a cap for said contact chamber, said plug having a closure member at the other end of 50 said explosion chambers and having a center contact pin extending through the closure member, the casing and the cap to hold the parts together, fuse elements extending from the contact chamber through the explosion chambers, and a shell contact around the plug with which the elements contact, said pin having a contact arm for engaging the fuse elements within the contact chamber.

60 2. A multiple fuse plug provided with a casing having a plurality of explosion chambers arranged around a central axis and having a contact chamber at one end of said explosion chambers, a cap for said contact chamber, said plug having a closure member at the other end of 65 said explosion chambers and having a center contact pin extending through the closure member, the casing and the cap to hold the parts together, said plug having vent passages running from said

explosion chambers through the closure member.

3. A multiple fuse plug provided with a casing having a plurality of explosion chambers arranged around a central axis and having a contact chamber at one end of said explosion chambers, a cap for said contact chamber, said plug having a closure member at the other end of said explosion chambers and having a center contact pin extending through the closure member, the casing and the cap to hold the parts together, said plug having vent passages between the casing and closure member and between the closure member and center pin.

4. A multiple fuse plug provided with a casing having a plurality of explosion chambers arranged around a central axis and having a contact chamber at one end of said explosion chambers, a cap for said contact chamber, said plug having a closure member at the other end of said explosion chambers and having a center contact pin extending through the closure member, the casing and the cap to hold the parts together, fuse elements extending from the contact chamber through the explosion chambers, 100 and a shell contact around the plug with which the elements contact, said pin having a contact arm for engaging the fuse elements within the contact chamber, said plug having a partition between the explosion chambers and the contact chamber.

5. A multiple fuse plug provided with a casing having a plurality of explosion chambers arranged around a central axis and having a contact chamber at one end of said explosion chambers, a cap for said contact chamber, said plug having a closure member at the other end of said explosion chambers and having a center contact pin extending through the closure member, the casing, and the cap to hold the parts together, 115 fuse elements extending from the contact chamber through the explosion chambers, and a shell contact around the plug with which the elements contact, said pin having a contact arm for engaging the fuse elements within the contact chamber, said plug having a transparent partition between the explosion chambers and the contact chamber, and said cap having means to render the partition visible therethrough for determining the condition of the fuse element.

6. A multiple fuse plug provided with a casing having a plurality of explosion chambers arranged around a central axis and having a contact chamber at one end of said explosion chambers, a cap for said contact chamber, said plug having a closure member at the other end of said explosion chambers and having a center contact pin extending through the closure member, the casing, and the cap to hold the parts together, 130 fuse elements extending from the contact chamber through the explosion chambers, and a shell contact around the plug with which the elements contact, said pin having a contact arm for engaging the fuse elements within the contact chamber, said plug having a partition between the explosion chambers and the contact chamber, and said cap having means to render the partition visible therethrough for determining when a fuse is blown.
